Wilson & Dunlap,

Pump Valve,

No 82,670,

Patented Sept. 29, 1868.

Fig. 1.

United States Patent Office.

CHARLES A. WILSON AND WILLIAM R. DUNLAP, OF CINCINNATI, OHIO.

Letters Patent No. 82,670, dated September 29, 1868.

IMPROVEMENT IN PUMPS.

The Schedule referred to in these Letters Patent and making part of the same.

TO WHOM IT MAY CONCERN:

Be it known that we, CHARLES A. WILSON and WILLIAM R. DUNLAP, both of Cincinnati, Hamilton county, Ohio, have invented a new and useful Valve for Pumps; and we hereby declare the following to be a full, clear, and exact description thereof, reference being had to the accompanying drawings, making part of this specification.

Our invention relates to a construction of valve for pumps which combines the advantages of large effective water-way with great mobility and ease of operation.

Figure 1 is an axial section through a valve embodying our invention, the same being in its open condition.

Figure 2 is a perspective view of one of the sections of our valve.

Our valve is composed of a stack or vertical series of hollow annular sections, A B C D, level on top, and traversed by numerous equidistant ports or passages, *a b c d*, of which the ports *b c d* communicate with the common interior of the valve, while the lower ones, *a*, open directly into the suction-pipe of the pump.

Secured by its inner edge, and resting upon the perforate top of each section, is an annular flap, E, of India rubber, or leather, or other pliable and impervious material.

Each section, except the lowest one, slopes inward on its under side, and serves at this part as a stop to limit the ascent of the flap below in the open condition of the latter.

To prevent the flap sticking fast to the under side of its superincumbent section, we furnish said under side with protuberances, F, against which the flap impinges when elevated.

Above the uppermost section is an annular flange, G, which curves upward and outward in the manner shown, so as to serve as a stop to the flap beneath it. Within the circuit of this flange, G, and closing the uppermost section, is a plate, H, having ports, *h*, guarded by a flap, E', which flap is restricted in its ascent by means of an annular flange, G'.

The flanges G and G' may be traversed by perforations having the same office as have the protuberances F. The flange G and plate H are preferably cast in one piece, as here represented.

The entire stack of seats is fastened together by bolts I and nuts J, so as to be readily detached for inspection or repair of any part. The bolts I traverse a bridge-piece, K, which is cast with the lower section A.

It will be seen that the inclining inward of each section, on the under side thereof, enables each to be of equal area to any, and affords facility for an aggregate area of ports of fully equal capacity to that of the suction-pipe.

We claim herein as new, and of our invention—

1. The combination of the annular valve-seats *a b c d* and annular valves E, when arranged in a vertical series, one above another, and constructed as herein described, so as to act simultaneously around the entire circumference.
2. In combination with the sections A B C D, with their described flexible flaps, we claim the annular stops or flanges G G'.
3. The protuberances F on the under side of the sections B C D, for the purpose explained.

In testimony of which invention, we hereunto set our hands.

CHARLES A. WILSON.
WILLIAM R. DUNLAP.
